Related U.S. Application Data

The ornamental design for a sport tights, as shown and described.

(62) Division of application No. 29/417,837, filed on Apr. 10, 2012, now Pat. No. Des. 681,916.

DESCRIPTION

(51) **LOC (10) Cl.** 02-02

FIG. 1 is a front view of a sport tights of the present invention.

(52) **U.S. Cl.**

FIG. 2 is a rear view of the sport tights of FIG. 1.

USPC **D2/738; D2/742**

FIG. 3 is a top plan view of the sport tights of FIG. 1.

(58) **Field of Classification Search**

FIG. 4 is a bottom view of the sport tights of FIG. 1.

USPC D2/731, 738, 742, 712, 857, 983;

2/227, 228, 238, 404, 247, 250-253,

2/242

See application file for complete search history.

FIG. 5 is a right side view of the sport tights of FIG. 1.

(56) **References Cited**

FIG. 6 is a left side view of the sport tights of FIG. 1.
